UNITED STATES PATENT OFFICE

148,558

DESIGN FOR A LAPEL AND POCKET BADGE OR SIMILAR ARTICLE

Robert J. Neller, Appleton, Wis.

Application July 8, 1946, Serial No. 131,367

Term of patent 3½ years

(Cl. D45—19)

To all whom it may concern:

Be it known that I, Robert J. Neller, a citizen of the United States, residing at Appleton, in the county of Outagamie and State of Wisconsin, have invented a new, original, and ornamental Design for a Lapel and Pocket Badge or Similar Article, of which the following is a specification, reference being had to the accompanying drawing, forming part thereof.

In the drawing:

Figure 1 is a front view, slightly in perspective, of a lapel and pocket badge showing my new design; and

I claim:

The ornamental design for a lapel and pocket badge or similar article, as shown.

ROBERT J. NELLER.
